WEFT DETECTING MECHANISM

Application filed December 9, 1930. Serial No. 501,081.

This invention relates to mechanism for detecting the substantial exhaustion of weft in a running shuttle. In the operation of automatic looms in which very fine or delicate filling is used, repeated blows of the detector on the filling sometimes weakens the filling or otherwise injures the same.

It is the object of my invention to provide an improved actuating mechanism for a weft detector by which the contact of the detector with the weft or filling is more gradually effected.

To the accomplishment of this object, I preferably mount the weft detector on the lay and cause the detector to move rearward on the lay toward the weft carrier at a slow relative speed as the lay approaches front center.

I have also provided novel mechanism for withdrawing the detector upon transfer of a weft carrier.

My invention further relates to arrangements and combinations of parts which will be hereinafter described and more particularly pointed out in the appended claims.

A preferred form of the invention is shown in the drawings, in which

Fig. 1 is a side elevation of parts of a loom embodying my invention, the lay being shown in section;

Fig. 2 is a front elevation of the mechanism shown in Fig. 1;

Fig. 3 is a sectional plan view, taken along the line 3—3 in Fig. 1 and with certain parts omitted;

Fig. 4 is a sectional plan view of certain parts, taken substantially along the line 4—4 in Fig. 2, and

Figs. 5 and 6 are detail views illustrating the operative connections of the weft detector.

Referring to the drawings, I have shown portions of a loom frame 10 on which is mounted a weft carrier magazine M of any usual type. A transerrer 11 is pivoted at 12 on the magazine M and is provided with a depending arm 13 to which the usual latch 14 is pivoted. Upon indication of transfer, a link 15 is moved upward and swings the latch 14 into position for engagement by a

bunter 16 mounted on the front of the lay 18.

When the latch is thus engaged by the bunter, the transerrer is rocked to force a bobbin or weft carrier B downward into the running shuttle S. The parts thus far described are of the usual construction and form no part of my present invention.

A side-slipping weft detector 20 (Fig. 3) is pivoted at 21 on a slide 22 mounted in guideways in a stand 23 secured to the front side of the lay 18. The slide 22 has a depending front end portion 24. A forwardly projecting portion 25 of the detector 20 moves normally alongside an upwardly projecting arm 27 (Fig. 5), mounted on a fixed pivot 28 and provided with a weight W which normally holds the arm 27 against a stop pin 29.

A chopper lever 30 is pivoted at 31 at the lower end of a rod or link 32 and is given a regular rocking movement by an actuator 33 pivoted at an intermediate point 34 on the lever 30. Under normal conditions, the lever 30 swings freely about its pivot 31 and no indication of transfer is given.

When the weft on the bobbin B is substantially exhausted, the detector 20 slides to the right in Fig. 3 and the forwardly projecting arm 25 moves to the left as indicated in Fig. 6, pushing the arm 27 into the path of movement of the free end of the chopper lever 30. The lever thereafter swings about its point of engagement with the arm 27 and the link 32 is moved downward, thus initiating the release of a fresh bobbin and the replenishment of the substantially exhausted shuttle.

The depending portion 24 of the detector slide 22 engages an upwardly extending arm of a bell crank lever 40, pivoted at 41 on an arm 42 which is preferably formed integral with the detector stand 23.

A cam roll 43 is mounted on a rearwardly extending arm of the bell crank lever 40 and engages a cam surface 44 formed on the upper edge of a bracket 45, fixed to a front portion of the loom frame 10. As the lay moves rearward, the roll 43 engages a rising portion of the cam 44 and the detector slide 22 and detector 20 are thus moved forward out of the shuttle box 45' and against the pressure of a spring 46 in the detector casing.

As the lay moves forward, the roll 43 follows a descending cam surface and permits the detector 20 to move relatively rearward under the influence of the spring 46 and to thus enter the shuttle S to detect the presence or absence of weft on the bobbin B.

By suitably designing the cam surface 44, the movement of the detector 20 into the shuttle S may be made as gradual and easy as may be desired.

After the detector engages the weft on the bobbin, the detector 20 and slide 22 move forward away from the bell crank lever 40.

It is necessary that the detector be withdrawn from the shuttle when a weft carrier transfer takes place and I have provided special mechanism for effecting such withdrawal. For this purpose I provide a movable cam plate 50, pivoted at 51 to the rear end of the bracket 45 and having its front end pivotally connected by a link 52 to a stud 53 in an ear 54 projecting forward from the transerrer 11.

Whenever the transerrer is operated to insert a fresh weft carrier B, the link 52 moves upward, raising the cam plate 50. The cam roll 43 overlies the cam plate 50 as well as the cam surface 44 and is moved upward by the raising of the cam plate 50, thus promptly withdrawing the detector 20 from the shuttle S as the transerrer descends.

I have thus provided simple and effective mechanism for permitting a detector to move into a shuttle at any desired relative speed and also for withdrawing the detector upon transfer. I am thus able to operate weft detecting mechanism with any kind of weft or filling, no matter how fine or delicate it may be.

Having thus described my invention and the advantages thereof, I do not wish to be limited to the details herein disclosed, otherwise than as set forth in the claims, but what I claim is:—

1. In a loom having a lay and a shuttle box, in combination, a weft detector mounted on said lay, a withdrawing lever mounted on said lay for said detector, a fixed cam engaging and operating said lever, and a second cam movable with respect to said first cam upon weft carrier transfer and effective to render said withdrawing lever operative at front center.

2. The combination in a loom as set forth in claim 1, in which the loom has a transerrer and in which the movable cam is directly connected to the transerrer and is moved in predetermined relation thereto.

3. In a loom having a lay and a shuttle box, in combination, a weft detector mounted on said lay, a spring to move said detector toward the shuttle box, means to withdraw said detector, an unyielding member fixed in position in the loom and normally effective to actuate said withdrawing means as the lay

moves forward, a second member movably mounted in the loom, and means effective to cause said second member to withdraw said detector during weft carrier transfer.

In testimony whereof I have hereunto affixed my signature.

OSCAR V. PAYNE.
